RATCHET FOR SOCKET WRENCHES

Willard C. Kress, Buffalo, N. Y., assignor to J. H. Williams & Co., Buffalo, N. Y.

Application November 16, 1944, Serial No. 563,771

13 Claims. (Cl. 192—43.1)

1

This invention relates to ratchet drives, and particularly to those utilized with tools such as socket wrenches and the like.

An object of the invention is to provide an improved ratchet drive which can be set to drive in either direction selectively and ratchet in the other direction, in an intermediate position in which it does not ratchet in either direction and thus serves as a direct coupling drive between the driving and driven parts, and which will be relatively simple, strong, durable, compact, easily manipulated and inexpensive.

Another object of the invention is to provide an improved ratchet drive having the various operating parts well enclosed, so as to be protected against the entrance of dirt and other foreign matter, and large power transmitting capabilities in a small compact space, which may be set to cause the drive in either direction or in both directions at will by a simple operation of a conveniently positioned control member, with which the control member will remain in its different adjusted positions until the coupling is definitely changed, and which will require a minimum of servicing and attention.

Other objects and advantages will be apparent from the following description of one embodiment of the invention, and the novel features will be particularly pointed out hereinafter in connection with the appended claims.

In the accompanying drawing:

Fig. 1 is a side elevation, at full scale, of a ratchet drive constructed in accordance with this invention;

Fig. 2 is a plan of the same;

Fig. 3 is a longitudinal sectional elevation of the same on an enlarged scale, the section being taken approximately along the line 3—3 of Fig. 2;

Fig. 4 is a bottom sectional plan of the same, the section being taken approximately along the line 4—4 of Fig. 3, and looking in the direction of the arrows;

Fig. 5 is a longitudinal sectional elevation of the same, the section being taken approximately along the line 5—5 of Fig. 4;

Fig. 6 is a bottom sectional plan of the same, the section being taken approximately along the line 6—6 of Fig. 5 and looking in the direction of the arrows; and

Fig. 7 is an elevation of the cam disc forming a part of the control of the direction of effectiveness of the drive.

In the illustrated embodiment of the invention, the ratchet drive includes a hollow, barrel shaped element or outer part 1, generally in the form of

2

a cylindrical shell having an open end 2 and a closed end 3. The closed end 3 has an axial extension 4 which is non circular and preferably square or hexagonal in transverse cross section, it being square in the particular example illustrated. In one of the faces of this extension is a ball 5 pressed outwardly by a spring, not shown, to slightly less than half way out so as to form a spring operated detent for engaging in a recess in the socket of a member to be coupled thereto as a part of the drive.

The inside of the barrel part 1 is generally cylindrical in shape, and around this inner periphery of this barrel 1 is a row of teeth 6. The individual teeth run in a direction lengthwise of this chamber in the barrel part or element 1, and are all arranged side by side and parallel to one another, but in a row around the periphery of the chamber. This row of teeth is shown particularly in Figs. 4 and 6. These teeth are preferably V shaped in character, with the dihedral angle of the apex approximately a right angle.

Another element or inner part 7 telescopes into the chamber of the barrel part or element through the open end 2, and has a cylindrical part 8 engaging a corresponding cylindrical portion 9 in the chamber of the element 1, to provide a bearing surface between them. The bearing surface 9 is between the open end 2 and the row of teeth 6.

The part 7 has a cylindrical bearing end 10 which is substantially concentric with the axis of the bearing surface 8, and at its free end it approximately abuts against the inner end wall 3 of the barrel or part 1 to transmit thrust between

the parts 1 and 7 in an endwise direction. Between the bearing portion 8 and the bearing end 10, this inner part 7 has cut away portions or grooves 11 and 12 running in a direction endwise of the part 7 and these two cut away portions 11 and 12, between them, have a V-shaped wall 13 with the apex outermost.

Formed in the bottom of the cut away portion 11 is a concave, partially cylindrical bearing 14 (Fig. 6) having a length approximately equal to the lengths of the teeth 6 and extending in transverse section slightly more than a half circle. The cut away portion 12 has a similar bearing surface 15. A ratchet pawl 16 has a partially cylindrical, convex surface 17 along one edge which fits and is rotatably received in the bearing 14, this bearing surface 17 being considerably in excess of a half cylinder, so that the pawl 16 may rock in the bearing 14 through a substantial angle. Similarly, a pawl 18 has a convex, cylindrical bearing portion 19 along one edge which is

rockably mounted in the bearing 15, this bearing surface 19 being considerably more than a half cylinder, so that the pawl 18 may rock through a considerable angle in the bearing 15. Both pawls 16 and 18 can abut against the converging walls that form the wall 13, as shown by the position of the pawl 18 in Fig. 6.

Each of the pawls 16 or 18 at its outer or free end is provided with a notch 20 of approximately 90° and engageable over any one of the V shaped teeth 6 aligned therewith at any time, as shown, for example, by the position of the pawl 16 in Fig. 6. One wall of each notch 20 is approximately normal to a radius to the cylindrical bearing 17 or 19 of that pawl, so that when the notch 20 is engaged over a tooth 6, as shown by the position of the pawl 16 in Fig. 6, that wall of the notch 20 which is normal to the radius to the bearing of that pawl will be in full abutting relation, flatwise, against one face or wall of that tooth 6 over which the notch 20 is engaged, and provides a direct thrust on that tooth 6 through the bearing axis of that pawl. Thus, when either pawl is in engagement with the teeth 6, it will provide a drive between parts 1 and 7, and there will be no camming action arising through the transmission of force between the parts, which would tend to disengage either pawl from the teeth. The teeth, however, may move away from either pawl in one direction, and each pawl may ride freely over the teeth when the edge of the pawl having the notch 20 is the trailing edge of the pawl during relative rotation of the parts 1 and 7. With the arrangement shown, the pawl 16 provides a direct drive between parts 1 and 7 in one direction and rides freely over the teeth in the other direction, and the pawl 18 provides a direct drive between the parts 1 and 7 during this other direction of relative movement and rides freely over the teeth 6 during said one direction of relative movement. When both pawls 16 and 18 engage teeth 6 at the same time, there is a full coupling between both parts 1 and 7 in both directions of relative movement.

In the face of each wall 11 and 12 there is a recess 21, Figs. 3, 5 and 6, in which is received a ball 22 that is urged outwardly by a helical compression spring 23, Fig. 6, but the outer end of each recess 21 is slightly constricted so as to prevent full ejection of the ball therefrom. These balls urge the pawls individually, resiliently, yieldingly and outwardly into engagement with the teeth 6 of the barrel part 1. The pawl 16 has a pin 24 extending therefrom in a direction parallel to the axis of rotation between the parts 1 and 7 and towards the inner end wall of the part 1. The other pawl 18 has a similar pin 25 extending in the same direction. A cam disc 26, as shown separately in Fig. 7, has a central bearing aperture 27 which is rotatably mounted on the bearing end 10 of the inner part 7, and abuts against the end of the wall 13. A notch or opening 28 is provided in the periphery of this cam 26 and into it the pins 24 and 25 extend. When the cam or disc 26 is rocked on the bearing end 10, the ends of the notch or opening 28 will alternately engage the pins 24 and 25 and carry those pins away from the adjacent teeth 6, so as to disengage the pawls alternately from the teeth 6.

In Fig. 4 one end of the notch 28 is shown as engaging the pin 25 and holding the pawl 18 disengaged from the teeth 6, and at the same time the other end of the notch 28 has fully released the pin 24 so that the pawl 16 can be urged into

engagement with the teeth 6 by its related spring pressed ball 22. If the cam or disc 26 is rocked to the left in Fig. 4, the pin 25 will be released so that pawl 18 may be urged yieldingly into engagement with the teeth 6, and immediately thereafter the opposite end of the notch 28 engages the pin 24 and cams the pawl 16 out of engagement with the teeth 6. Thus it will be observed that by rocking of the cam or disc 26 on the bearing end 10 of the part 7, the pawls 16 and 18 may be alternately disengaged from the teeth 6. The notch 28 is long enough, however, so that when the cam 26 is in an intermediate position, both pins 24 and 25 will be released sufficiently to enable both pawls 16 and 18 to fully engage with the ratchet teeth 6 of the barrel or part 1.

The face of the cam or disc 26 which abuts against the end of the V shaped wall 13 is provided with a radially extending slot or notch 29, see Fig. 7, which receives a cam 30, Figs. 4 and 5. This cam 30 is fixed upon one end of a rod or shaft 31 which extends parallel to and at one side of the axis of relative rotation between the parts 1 and 7 to a point outside of the barrel part 1, as shown in Fig. 5. This rod 31 is rotatably mounted in the part 7, and its outer end has a portion substantially exposed through a recess 32, see Fig. 1, provided in the periphery of the part 7 at the end exteriorly of the part 1. This exposed end of the rod 31 carries an operating handle 33, Figs. 1, 2 and 5, by which the rod 31 may be rocked to a limited extent, during which rocking movement the cam 30 on the inner end thereof alternately engages opposite sides of the notch or slot 29 in the cam 26 and rocks the latter about the bearing end 10 to alternately disengage the pawls 16 and 18 from the teeth 6.

A washer 34 is also rotatably mounted on the bearing end 10 and is disposed between the cam 26 and the inner end 3 of the outer part 1 as shown in Fig. 5. This washer is provided with a recess 35 on its face abutting the end 3, and a helical compression spring 36 is disposed in this recess 35 so as to urge the washer 34 against the end face of the cam 26 and provide some frictional resistance against movement of the cam 26. The periphery of the washer 34 has a bearing engagement with the cylindrical end portion of the chamber in the barrel element or part 1, and also has a bearing on the bearing end 10.

The part 7, at a zone just within the barrel element or part 1, has an outwardly facing shoulder 37, Figs. 3 and 5, formed by reducing the outwardly extending end of the part 7. The open end 2 of the part 1, at a short distance from its extreme open end, is provided with a circular groove 38. A split, resilient ring 39 is disposed in the groove 38 and extends radially and inwardly into the chamber of the barrel part and overlaps with the shoulder 37 to limit outward movement of the part 7 in a direction endwise of that part. The spring 36, by its endwise pressure on the washer 34 and the part 1, holds the shoulder 37 against the ring 39 as shown in Fig. 3. The part 7 may be pushed endwise and inwardly of the part 1 a small amount, to release pressure on the ring 39 and enable its removal when one desires to remove the inner part 7 from the outer part 1.

The outer end of the part 7 is provided with a non-circular recess 40 to receive a correspondingly squared end of a part of the drive. The recess 40 corresponds to the socket of a socket wrench, and is usually made hexagonal or square as may be desired, but in the example shown, 75 this recess or socket 40 is square in its periphery.

The open end 2 of the part 1 may have a notch or slot 41, Fig. 2, leading to the groove 38 to enable a tool to be inserted behind the ring 39 sufficiently to pry one part of the ring 39, adjacent the split therein, sufficiently to disengage it from the groove 38.

The cam 30 extends to one side of the rod 31 a further distance than the other, and the maximum width or diameter of the cam is less than the width of the radial slot 29 in the cam 26. The edge zones or portions of the cam 30 furthest from and nearest to the rod 31 are circular, with their centers of curvature at the longitudinal axis of the rod 31, so that when said circular edge zones of the cam 30 engages either side of the slot 29, the thrust between that side of the notch 29 and the cam 30 will not cause rotation of the cam. Thus, when the rod 31 is rocked in either direction, the circular peripheral zones of the cam 30 by engagement with the sides of the notch 29 of the cam 26 will hold the cam 26 in that adjusted position and prevent any danger of the cam 26 being accidentally shifted by any of the driving forces in a manner to change the control of the pawls thereby.

It is believed that the operation of the drive will be clear from the preceding description of the construction, but it will be briefly summarized. Assuming that the drive is assembled with the parts in the relation shown in Figs. 1 to 6, and that the extension 4 of part 1 is received in a socket of a part to be driven, and that a driving part has a square end disposed in the recess 40 in the outer end of part 7, the operator first operates the handle 33 to the end position which causes the release of the particular pawl which is to give the desired direction of drive. In Figs. 4 and 6 it is the pawl 16 which is released for engagement with the teeth 6, and the pawl 18 is disengaged from the teeth 6. When the inner part 7 is rotated counter clockwise in Fig. 4, it will impart a similar movement to the outer part 1, and when the inner part 7 is given a clockwise movement in Fig. 4, the pawl 16 will ratchet or ride idly over the teeth 6 during which there is no driving action between the parts 1 and 7.

If now the handle 33 is moved to its other end position, the cam 30 will be rocked from the position shown in Fig. 4 to the right, or clockwise in that figure, so as to rock the cam 26 in a direction to have one end of the notch 28 engage pin 24 on pawl 16 and disengage pawl 16 from the ratchet teeth 6, and immediately thereafter fully release the pin 25 on pawl 18 so that the pawl 18 may be yieldingly urged into engagement with the teeth 6 and provide a driving connection between the parts 1 and 7. With that relation of the parts, when the part 7 is given a clockwise rotation in Fig. 4, the pawl 18 would drive the part 1 in the same direction, but would ride idly over the teeth 6 during counter clockwise movement of the part 7 in Fig. 4.

If the handle 33 is moved into an intermediate position, where neither end of the slot 28 holds a pawl out of engagement with the teeth 6, then both pawls 16 and 18 will be free to be moved into engagement with the teeth 6 by their spring pressed balls 22, and one pawl will provide a direct drive in one direction, and the other pawl in the other direction, with no idle or ratchet movement whatever. Thus the device can be set to ratchet in one direction or the other selectively, or it may be placed in a locked condition in which there is no ratchet action, but a direct drive in both directions.

The handle 33 is conveniently positioned for adjustment, and all of the parts of the mechanism are fully enclosed so as to be protected from dirt and other foreign matter. It will also be noted that by having the pawls mounted for oscillation on axes which are parallel to the axis of rotation between the parts 1 and 7, the teeth engaging edges of the pawls may be made of substantial length, and the teeth 6 may also be made of substantial length. This gives substantial strength to the structure, and rather heavy driving forces may be transmitted with safety between the parts without danger of breakage of the pawls or other parts. The arrangement also accomplishes this heavy driving capacity with great compactness of the drive.

It will be understood that various changes in the details, materials and arrangements of parts, which have been herein described and illustrated in order to explain the nature of the invention, may be made by those skilled in the art within the principle and scope of the invention as expressed in the appended claims.

I claim:

- 25 1. A ratchet drive comprising a driving part and a driven part partially telescoping endwise and having cooperating bearing surfaces rotatably supporting one from the other, one of said parts having a peripherally extending row of teeth, the other of said parts mounting a pair of pawls for individual movement into and out of engagement with said teeth, one pawl, by its engagement with said teeth, preventing relative rotation of said parts in one direction and riding idly over the teeth in the other direction, and the other pawl, by its engagement with said teeth, preventing relative rotation of the parts in said other direction and riding idly over said teeth in said one direction, means resiliently urging both of said pawls individually into engagement with said teeth, said pawls having extensions at corresponding ends eccentric to their pivotal axes, and a disk disposed transversely across the ends of said pawls, 30 mounted for movement back and forth about the axis of relative rotation of said parts and having an opening into which said pawl extensions continuously project, said disk when rotated in either direction having one end of said 35 opening engaging the extension of one pawl and forcing it out of engagement with said teeth while the other end of the opening fully releases the extension on the other pawl, and disengaging said pawls alternately as said disk moves back 40 and forth, said opening having a length in the direction of movement of said disk greater than the distance between said extensions when both pawls engage with said teeth, whereby when said disk is in an intermediate angular position in 45 its adjustment, the ends of the opening will fully release both pawls for engagement with said teeth.

- 50 2. A ratchet drive comprising a driving part and a driven part partially telescoping endwise and having cooperating bearing surfaces rotatably supporting one from the other, one of said parts having a peripherally extending row of teeth, the other of said parts mounting a pair of pawls for individual movement into and out of engagement with said teeth, one pawl, by its engagement with said teeth, preventing relative rotation of said parts in one direction and riding idly over the teeth in the other direction, and the other pawl, by its engagement with said teeth, 55 preventing relative rotation of the parts in said 60

other direction and riding idly over said teeth in said one direction, means resiliently urging both of said pawls individually into engagement with said teeth, an element mounted on said part carrying said pawls and adjustable thereon between three positions in one of which it shifts one of said pawls out of engagement with said teeth, holds it so disengaged, and releases the other pawl, in another of which it shifts said other pawl out of engagement with said teeth, holds it so disengaged, and releases said one pawl, and in the third of which positions it releases both of said pawls concurrently, a shaft rockably mounted on said part carrying said pawls and extending in a direction parallel to the rocking axes of the pawls to a point exteriorly of the telescoping parts, said shaft at one end having a cam part engaging with said element to shift it between said positions when said shaft is rocked, and the outer end of said shaft having an operating handle by which it may be rocked in order to change the adjustments of said element.

3. A ratchet drive comprising a driving part and a driven part partially telescoping endwise and having cooperating bearing surfaces rotatably supporting one from the other, one of said parts having a peripheral row of longitudinally extending teeth, the other of said parts mounting a pair of pawls for individual movement into and out of engagement with said teeth, one pawl, by its engagement with said teeth, preventing relative rotation of said parts in one direction and riding idly over the teeth in the other direction, and the other pawl, by its engagement with said teeth, preventing relative rotation of the parts in said other direction and riding idly over said teeth in said one direction, means resiliently urging both of said pawls individually into engagement with said teeth, a cam disk extending across the ends of the pawls, mounted for rocking movement about an axis parallel to the rocking axes of said pawls and having an opening in the face towards the pawls in which the ends of the pawls are continuously received and extending in a direction about the rocking axis, said pawls being engaged alternately by the ends of said opening, a member mounted for oscillation about an axis parallel to, but eccentric of the axis of relative rotation between said parts and engageable with said disk to rock it selectively between two positions, in one of which one end of said opening shifts one of said pawls out of engagement with said teeth and holds it so disengaged while the opposite end of the opening releases the other pawl, and in another of which it shifts the other pawl out of engagement with said teeth, holds it so disengaged and releases the said one of said pawls, the opening being of a length, in the direction of movement of said disk, greater than the distance between said pawl ends when both pawls engage said teeth, whereby when said disk is in an intermediate position it releases both of said pawls for engagement with said teeth, said member being accessible for operation from the exterior of said telescoping parts, whereby said pawls may be selectively shifted while said parts remain assembled.

4. A ratchet drive comprising a driving part and a driven part partially telescoping endwise and having cooperating bearing surfaces rotatably supporting one from the other, one of said parts having a peripherally extending row of teeth, the other of said parts mounting a pair of pawls for individual movement into and out of

engagement with said teeth, one pawl, by its engagement with said teeth, preventing relative rotation of said parts in one direction and riding idly over the teeth in the other direction, and the other pawl, by its engagement with said teeth, preventing relative rotation of the parts in said other direction and riding idly over said teeth in said one direction, means resiliently urging both of said pawls individually into engagement with said teeth, said pawls having extensions at corresponding ends, an element mounted for movement back and forth about the axis of relative rotation of said parts and having a notch in which said pawl extensions are disposed, said element when rotated in either direction engaging the extension of one pawl and forcing it out of engagement with said teeth while the other end of the notch fully releases the extension on the other pawl, and disengaging said pawls alternately as said element moves back and forth, said notch having a length in the direction of movement of said element greater than the distance between said extensions when both pawls engage with said teeth, whereby when said element is in an intermediate position in its adjustment, the ends of the notches will fully release both pawls for engagement with said teeth, a rod rockably mounted about its longitudinal axis and extending parallel to the axis of rotation of said part carrying the pawls, and means fixed on the inner end of said rod and having a cam engagement with said element for rocking it between said different positions, said rod extending outwardly beyond the telescoping portions of said parts and there having an exposed portion accessible for operation when a shifting of said pawls is desired.

5. A ratchet device comprising a hollow, barrel part open at one end, an inner part partially telescoping endwise within said barrel part, said parts having cooperating bearing surfaces rotatably supporting one from the other, said barrel part having a row of teeth around its inner periphery, said inner part rockably mounting a pair of pawls for individual rocking movement about axes parallel to the axis of relative rotation of said parts, individually into and out of engagement with said teeth, one of said pawls, by its engagement with the teeth, preventing relative rotation of said parts in one direction and riding idly over the teeth in the other direction, the other of said pawls, by its engagement with said teeth, preventing relative rotation of the parts in said other direction and riding idly over the teeth in said one direction, means resiliently urging said pawls individually into engagement with said teeth, an element rockably mounted on said inner part adjacent the inner end of said barrel part and having an opening therein, and said pawls having eccentric pins extending into and continuously remaining in said opening so as to be alternately engaged by the ends of said opening when said element is rocked on said inner part, the ends of said notch alternately engaging and shifting said pawls out of engagement with said teeth while releasing the other pawl for engagement with said teeth, said notch having a length sufficient, when at an intermediate position, to fully release the pins of both pawls for simultaneous engagement of said pawls with said teeth, and means engaging said element extending from said element lengthwise of the barrel part to its outer end and there accessible for operation from the exterior of said telescoping parts for rocking said element in opposite directions

to control the engagement of said pawls with said teeth.

6. A ratchet device comprising a hollow, barrel part open at one end, an inner part partially telescoping endwise within said barrel part, said parts having cooperating bearing surfaces rotatably supporting one from the other, said barrel part having a row of teeth around its inner periphery, said inner part rockably mounting a pair of pawls for individual rocking movement about axes parallel to the axis of relative rotation of said parts, individually into and out of engagement with said teeth, one of said pawls, by its engagement with said teeth, preventing relative rotation of said parts in one direction and riding idly over the teeth in the other direction, the other of said pawls, by its engagement with said teeth, preventing relative rotation of the parts in said other direction and riding idly over the teeth in said one direction, means resiliently urging said pawls individually into engagement with said teeth, an element rockably mounted on said inner part adjacent the inner end of said barrel part and having an opening therein, and said pawls having pins extending into and always remaining in said opening so as to be alternately engaged by the ends of said opening when said element is rocked on said inner part, the ends of said notch alternately engaging and shifting said pawls out of engagement with said teeth while releasing the other pawl for engagement with said teeth, said notch having a length greater than the distance between said pins and sufficient, when at an intermediate position, to fully release the pins of both pawls for simultaneous engagement of said pawls with said teeth, means engaging said element extending lengthwise of said parts to the open end of the barrel part and there accessible for operation from the exterior of said telescoping parts for rocking said element in opposite directions to control the engagement of said pawls with said teeth, and means at the inner end of said barrel and acting between said barrel part and said element for frictionally resisting movement of said element on said inner part.

7. A ratchet device comprising a hollow, barrel part open at one end, an inner part partially telescoping endwise within said barrel part, said parts having cooperating bearing surfaces rotatably supporting one from the other, said barrel part having a row of teeth around its inner periphery, said inner part rockably mounting a pair of pawls for individual rocking movement about axes parallel to the axis of relative rotation of said parts, individually into and out of engagement with said teeth, one of said pawls, by its engagement with said teeth, preventing relative rotation of said parts in one direction and riding idly over the teeth in the other direction, the other of said pawls, by its engagement with said teeth, preventing relative rotation of the parts in said other direction and riding idly over the teeth in said one direction, means resiliently urging said pawls individually into engagement with said teeth, an element rockably mounted on said inner part adjacent the inner end of said barrel part and having an opening therein, and said pawls having pins extending into said opening so as to be alternately engaged by the ends of said opening when said element is rocked on said inner part, the ends of said notch alternately engaging and shifting said pawls out of engagement with said teeth while releasing the other pawl for engagement with said teeth, said notch

having a length sufficient, when at an intermediate position, to fully release the pins of both pawls for simultaneous engagement of said pawls with said teeth, means engaging said element and accessible for operation from the exterior of said telescoping parts for rocking said element in opposite directions to control the engagement of said pawls with said teeth, a washer disposed between the inner part and the inner end of said barrel part and having an end face bearing against said element so as to frictionally retard its rocking movement on said inner part, and a spring acting between the inner end of said barrel part and said washer, and urging said washer endwise against said element so as to frictionally hold said element in its different adjusted positions.

8. A ratchet device comprising a hollow, barrel part open at one end, an inner part partially telescoping endwise within said barrel part, said parts having cooperating bearing surfaces rotatably supporting one from the other, said barrel part having a row of teeth around its inner periphery, said inner part rockably mounting a pair of pawls for individual rocking movement about axes parallel to the axis of relative rotation of said parts, individually into and out of engagement with said teeth, one of said pawls, by its engagement with said teeth, preventing relative rotation of said parts in one direction and riding idly over the teeth in the other direction, the other of said pawls, by its engagement with said teeth, preventing relative rotation of the parts in said other direction and riding idly over the teeth in said one direction, means resiliently urging said pawls individually into engagement with said teeth, an element rockably mounted on said inner part adjacent the inner end of said barrel part and having an opening therein, and said pawls having pins extending into said opening so as to be alternately engaged by the ends of said opening when said element is rocked on said inner part, the ends of said notch alternately engaging and shifting said pawls out of engagement with said teeth while releasing the other pawl for engagement with said teeth, said notch having a length sufficient, when at an intermediate position, to fully release the pins of both pawls for simultaneous engagement of said pawls with said teeth, a rod extending in a direction lengthwise of said inner part and rockably mounted for oscillation on its own axis, by said inner part, and a connection between the inner end of said rod and said element for transmitting rocking movements of said rod into rocking movements of said element, said rod extending out of the telescoping relation between said parts and having its outer end exposed for manual rocking operation.

60 9. A ratchet device comprising a hollow, barrel part open at one end, an inner part partially telescoping endwise within said barrel part, said parts having cooperating bearing surfaces rotatably supporting one from the other, said barrel part having a row of teeth around its inner periphery, said inner part rockably mounting a pair of pawls for individual rocking movement about axes parallel to the axis of relative rotation of said parts, individually into and out of engagement with said teeth, one of said pawls, by its engagement with said teeth, preventing relative rotation of said parts in one direction and riding idly over the teeth in the other direction, the other of said pawls, by its engagement with said teeth, preventing relative rotation of

the parts in said other direction and riding idly over the teeth in said one direction, means resiliently urging said pawls individually into engagement with said teeth, an element rockably mounted on said inner part adjacent the inner end of said barrel part and having an opening therein, and said pawls having pins extending into said opening so as to be alternately engaged by the ends of said opening when said element is rocked on said inner part, the ends of said notch alternately engaging and shifting said pawls out of engagement with said teeth while releasing the other pawl for engagement with said teeth, said notch having a length sufficient, when at an intermediate position, to fully release the pins of both pawls for simultaneous engagement of said pawls with said teeth, a rod extending in a direction lengthwise of said inner part and rockably mounted for oscillation on its own axis, a connection between the inner end of said rod and said element for transmitting rocking movements of said rod into rocking movements of said element, said rod extending out of the telescoping relation between said parts and having its outer end exposed for manual rocking operation, a washer disposed between the inner end of said barrel part and said element, a spring acting between the inner end of said barrel part and said washer for urging said washer endwise against said element and frictionally resisting rocking movement of said element, whereby said element will retain the positions into which it is adjusted by said rod.

10. A ratchet drive comprising a hollow barrel part having an open end, an inner part telescoping within said barrel part through said open end, said barrel part adjacent its open end having an annular groove in its inner periphery, and said inner part having a peripherally extending shoulder approximately aligned, transversely of the parts, with the inner side wall of said groove, a split ring releasably engaged in said groove and overlying said shoulder so as to prevent endwise retraction of said inner part from said barrel part, the inner periphery of said barrel part having teeth extending in a direction lengthwise thereof and arranged in a row around said inner periphery, said telescoping parts having cooperating bearing surfaces by which one part is rotatably connected to the other, a pair of pawls carried by said inner part within said barrel part and rockably mounted on axes parallel to the axis of relative rotation between said parts, spring means urging said pawls individually into engagement with said teeth, one of said pawls preventing relative rotation of said parts in one direction while riding idly over the teeth in the other direction, and the other of said pawls, by its engagement with said teeth, preventing relative rotation of said parts in said other direction while riding idly over said teeth in said one direction, and means carried by said inner part, engageable for operation from the exterior of the barrel part, and operable on said pawls by movement between selected positions, to shift them alternately out of engagement with said teeth and hold each disengaged while releasing the other pawl, and, when in another position, fully releasing both of said pawls for simultaneous engagement with said teeth to prevent relative rotation of said parts in both directions.

11. A ratchet drive comprising a hollow barrel part having an open end, an inner part telescoping within said barrel part through said open

end, said barrel part adjacent its open end having an annular groove in its inner periphery, and said inner part having a peripherally extending shoulder approximately aligned, transversely of the parts, with the inner side wall of said groove, a split ring releasably engaged in said groove and overlying said shoulder so as to prevent endwise retraction of said inner part from said barrel part, the inner periphery of said barrel part having teeth extending in a direction lengthwise thereof and arranged in a row around said inner periphery, said telescoping parts having cooperating bearing surfaces by which one part is rotatably connected to the other, a pair of pawls carried by said inner part within said barrel part and rockably mounted on axes parallel to the axis of relative rotation between said parts, spring means urging said pawls individually into engagement with said teeth, one of said pawls preventing relative rotation of said parts in one direction while riding idly over the teeth in the other direction, and the other of said pawls, by its engagement with said teeth, preventing relative rotation of said parts in said other direction while riding idly over said teeth in said one direction, means carried by said inner part, engageable for operation from the exterior of the barrel part, and operable on said pawls, by movement between selected positions, to shift them alternately out of engagement with said teeth and hold each disengaged while releasing the other pawl, and, when in another position, fully releasing both of said pawls for simultaneous engagement with said teeth to prevent relative rotation of said parts in both directions, a washer interposed between the inner end of the barrel part and said last named means for frictionally holding the latter in its different positions, and a spring acting between the inner end of said barrel part and said washer and urging said washer in a direction outwardly of said barrel part to provide the frictional contact with said pawl shifting means, and for holding said shoulder against said split ring.

45. 12. A ratchet device comprising a barrel part having one open end and closed at the other end, an inner part partially telescoping into said barrel part, the telescoping portions of said parts having cooperating bearing surfaces by which the parts may have relative rotation about an axis parallel to the lengths of said parts, the inner wall of said barrel part adjacent its open end having an inwardly facing shoulder, and said inner part having adjacent thereto an outwardly facing shoulder, a split ring disposed between said shoulders so as to releasably lock said parts together against endwise separation, the chamber within said barrel part having a peripherally arranged row of teeth, a pair of pawls carried by said inner part extending approximately to the inner end of said barrel part and movable individually into and out of engagement with said teeth, resilient means urging said pawls individually into engagement with said teeth, one of said pawls, by its engagement with said teeth, preventing relative rotation of parts in one direction and riding idly over the teeth in the other direction, and the other of said pawls, by its engagement with said teeth, preventing relative rotation of said parts in said other direction and riding idly over said teeth in said one direction, a rod extending parallel to the axis of rotation between said parts, from adjacent the inner end of the barrel part to and beyond the open end of said barrel part, and rotatably sup-

13

ported by the inner part between the peripheral wall of said inner part and the axis of rotation of said parts, a member operated by the inner end of said rod for shifting said pawls alternately and individually out of engagement with said teeth or releasing both of said pawls concurrently, and a manually operable terminal on the outer end of said rod.

13. A ratchet device comprising a barrel part having one open end, an inner part partially telescoping into said barrel part, the telescoping portions of said parts having cooperating bearing surfaces by which the parts may have relative rotation about an axis parallel to the lengths of said parts, the inner wall of said barrel part adjacent its open end having an inwardly facing shoulder, and said inner part having adjacent thereto an outwardly facing shoulder, a split ring disposed between said shoulders so as to releasably lock said parts together against endwise separation, the chamber within said barrel part having a peripherally arranged row of teeth, a pair of pawls carried by said inner part and

14

movable individually into and out of engagement with said teeth, resilient means urging said pawls individually into engagement with said teeth, one of said pawls, by its engagement with said teeth, preventing relative rotation of parts in one direction and riding idly over the teeth in the other direction, and the other of said pawls, by its engagement with said teeth, preventing relative rotation of said parts in said other direction and riding idly over said teeth in said one direction, a motion transmitting element for shifting said pawls alternately and individually out of engagement with said teeth or releasing both of said pawls concurrently, said element having a portion accessible for operation exteriorly of said barrel part, a washer disposed between said element and the inner end of said barrel, and a spring acting between said inner end and said washer and urging the latter against said element to frictionally retard its movements in shifting said pawls, and also holding said shoulder against said ring.
